UNITED STATES PATENT OFFICE

HENRI BÜNZLI, OF PATERSON, NEW JERSEY.

SHEDDING MECHANISM FOR LOOMS.

SPECIFICATION forming part of Letters Patent No. 271,033, dated January 23, 1883.

Application filed May 8, 1882. (No model.)

To all whom it may concern:

Be it known that I, HENRI BÜNZLI, a citizen of the United States, residing at Paterson, New Jersey, have invented new and useful 5 Improvements in Sheding Mechanisms for Looms, of which the following is a specification.

This invention, which relates to the shedding mechanism of looms, consists in certain novel combinations of parts, that will be hereinafter 10 more fully described, and specifically set forth in the claims.

In the annexed drawings, Figure 1 is a rear view of a portion of my improved mechanism; Fig. 2, a side view of the same. Fig. 3 is an 15 elevation of one of the heddle-frames, showing the manner of suspending the same; and Fig. 4 is a sectional plan view on the dotted line shown in Fig. 3.

In the said drawings, A designates part of 20 the frame-work of an ordinary loom, upon which is mounted the frame B of my improved shedding mechanism. A lever, a, fulcrumed at c to the frame B, operates the shedding mechanism, said lever being vibrated upon its fulcrum by a link, b, which receives motion from a 25 crank or other means. This lever a performs three distinct functions, namely: first, effecting the movement of the heddles, which are to be raised; second, effecting the movement 30 of the heddles which are to be lowered, and, third, effecting the movement of the pattern or jacquard cylinder.

The heddle-frames H, Fig. 3, are suspended 35 by cords d from the strips d' and hooks d''. These hooks d'' pass through eyes e of the needles n, and their upper ends are fitted to engage with the levers f when the needles are permitted to enter holes in the jacquard-cylinder. The levers f are pivoted at g to brackets 40 x of the frame B, and their ends h are joined or secured to the arms of a forked link, l, the lower end of which is slotted and connected by a pin or otherwise to the lever a, from which it receives an up-and-down motion as the lever 45 is vibrated by the link b.

J is a pattern or jacquard cylinder of the ordinary construction, such as is usually employed in looms of this class, and as its construction and operation are well known, and 50 as it forms no part of my present invention, it is not deemed necessary to herein describe it in detail, it sufficing to say that the cylinder

is capable of revolution on its axis, and that it may be swung away from the needles, motion being imparted to it from the lever a and arms q and s, whereby when lever a is operated so as to swing the arms s outward the cylinder carried by said arms will strike against hook q', which will turn it one-quarter of a revolution; but as the mechanism for thus 60 operating the pattern or jacquard cylinder will be found in numerous patents, and as its operation, in connection with the hooks and heddle-frames, is similar to the ordinary and well-known jacquard mechanism, further description is not deemed necessary. The needles n are operated by the cards of the jacquard-cylinder, and such of the hooks d'' as are carried by the needles which enter the perforations in the cards will remain in the path of the levers 70 f, and when the latter ascend they will engage with the hooked ends of said hooks and cause the same and their respective heddle-frames to be raised and the warp-threads shifted.

To the brackets y of the frame B are pivoted 75 at j the levers i. These levers are actuated by the lever a through the connection consisting of the links k k and m m and intermediate pivoted levers, o o. The links k are connected respectively at their opposite ends to the levers a 80 and o, while the links m are connected to the levers o and i. It will be seen that by this connection the levers i will be depressed by the upward movement of the lever a, for as the lower ends of the pivoted levers o are raised by the lever 85 a and links k their upper ends will be depressed and thus cause the depression of the levers i. When the movement of the lever a is reversed and it is caused to descend, the movement of said connecting links and levers is reversed; 90 and the levers i accordingly raised. It will thus be seen that the levers f and i work inversely to each other—that is, as one ascends the other descends, and vice versa.

The strips d', by which the heddle-frames are suspended, (see Figs. 2 and 3,) pass through openings in the lever i, and are provided with shoulders or enlargements p at their upper ends. These shoulders or enlargements rest upon the levers i, and when the latter ascend 100 the strips are also raised.

W is a weight attached to each of the heddle-frames by the cords w, by the gravity of which the heddle-frames will be carried down

when they are permitted to descend by the levers *i*.

When the apparatus is to be operated by hand, a lever, *r'*, (shown in dotted lines,) may be pivoted at *r*, and connected by rods or other suitable means to the forked bar or link *l*. The lever *r'* can be connected by a cord, *r²*, with a suitable treadle, said cord being also shown in dotted lines.

10 The operation of my improved mechanism is as follows: The parts being in the position shown in Fig. 1, the lever *a* is caused to ascend, carrying with it the forked link *l*, which raises the levers *f*. These levers will engage with the hooks *d²*, which have not been pushed aside by the cards of the jacquard-cylinder, and raise them, and consequently the heddle-frames to which they are respectively connected. At the same time levers *i* will descend, and such of the hooks as have been moved out of engagement with levers *f* by the card-cylinder and needles will descend with said levers. When the lever *a* has reached the end of its stroke its movement will be reversed, causing a reversal of the movement of the levers *f* and *i*, which will now approach each other, and when the enlargements *p* meet the levers *i* the hooks will become disengaged from the levers *f*, and the succeeding card of the jacquard-cylinder

15 may make a new selection through the needles *n*.

What I claim is—

1. The combination of the levers *f*, forked link *l*, lever *a*, hooks *d²*, the needles *n*, a jacquard-cylinder, means for operating said cylinder, the heddle-frames *H*, weights *W*, and means for connecting said frames with said hooks, substantially as described. 35

2. The combination of the levers *i*, links *k* *m*, intermediate levers, *o*, the lever *a*, suspension-strips *d'*, having enlargements *p*, the heddle-frames *H*, and weights *W*, substantially as described. 40

3. The combination of the levers *f* and *i*, forked link *l*, links *k* *m*, intermediate levers, *o*, and the lever *a*, substantially as described. 45

4. The combination of the levers *f* and *i*, the forked link *l*, links *k* *m*, intermediate levers, *o*, lever *a*, hooks *d²*, strips *d'*, having enlargements *p*, cords *d*, heddle-frames *H*, and weights *W*, substantially as described. 50

In testimony whereof I have hereunto set my hand in the presence of two subscribing witnesses.

HENRI BÜNZLI.
